METHOD OF INHIBITING GUM FORMATION
IN CRACKED HYDROCARBONS

George W. Ayers, Jr., Chicago, Ill., assignor, by
mesne assignments, to Gasoline Antioxidant
Company, Chicago, Ill., a corporation of Del-
aware

No Drawing. Original application April 28, 1932,
Serial No. 608,148. Divided and this applica-
tion May 13, 1937, Serial No. 142,491

3 Claims. (CL. 44—9)

This application is a division of application
Serial No. 608,148, filed April 28, 1932, which ap-
plication is a continuation-in-part of Serial Num-
ber 309,685, filed October 1, 1928, in which ap-
plication I have disclosed the treatment of cracked
5 highly unsaturated hydrocarbon motor fuel dis-
tillates of less-readily detonating type, with vari-
ous chemical compounds for the purpose of in-
hibiting development (or otherwise curing the
10 same) of gum deposits or objectionable color, or
both.

Cracked petroleum products, particularly gaso-
line, upon being exposed for some time to air,
light or heat, form resinous materials which may
15 be dissolved by the petroleum product or which
may form an insoluble deposit. These resinous
products are formed particularly in large amounts
when vapor phase gasoline, that is, gasoline
which contains a large percent of unsaturated
20 compounds, is stored for several months. If a
tank of such gasoline, for example, were exposed
for some time to the heat of the sun or to con-
tact with air or both, formation of these undesir-
able resinous products would ordinarily take
25 place. If these gums were permitted to form
and remain in the motor fuel product, they would
seriously interfere with the proper flow of the
motor fuel through the fuel passages of internal
combustion engines by clogging such passages
30 against the free and proper flow of the fuel to
the combustion cylinders. On the other hand, it
is important to have a large amount of unsat-
urates present in the gasoline, since such unsat-
urated compounds give the motor fuel a high
35 anti-knock value. The problem, of course, is to
keep them in the fuel, without forming objection-
able gums, resins, or color.

In application Ser. No. 309,685 hereinabove
mentioned, I have disclosed a number of tests
40 upon various organic compounds for the purpose
of inhibiting the formation of gums and resins
in cracked motor fuels, and for the purpose of
stabilizing the characteristics of cracked gasoline.
Among such compounds tested were hydrocarbons
45 having more than one benzene ring as a nucleus,
comprising those hydrocarbons classifiable as
aromatic hydrocarbons having a plurality of com-
bined benzene rings; and also polyhydroxy-aro-
matic compounds generally. Specifically, I dis-
50 closed in the aforesaid application Ser. No. 309,-
685, examples of gum inhibiting tests upon hy-
drocarbons having more than one benzene nu-
cleus such as alpha-naphthylamine, beta-naph-
thol, and others, and in the present application it
55 is my desire to restrict my claims to polyhydroxy

aromatic compounds broadly, and specifically to
the hydroxy compounds of the poly-nuclear ben-
zene ring. Such hydroxy compounds have been
found to possess qualities which render them
adapted as negative catalysts or inhibitors, and
as disclosed in my prior application, the best in-
hibiting effect is obtained with the compounds
having the greatest number of hydroxy groups.
It will be, of course, understood that other hy-
droxy compounds of the polyhydroxy aromatic 10
group may also be used, such as 1:4-dihydroxy-
naphthalene [$C_{10}H_8(OH)_2$]; 1:2-dihydroxynaph-
thalene; alizarin

dihydroxyphenanthrene [$C_{14}H_8(OH)_2$]; and
others of this classification.

I prefer to treat the cracked distillate with a
polymerizing catalyst such as fuller's earth prior
to the addition of any of the aforesaid gum in-
hibiting agents or combination of the same. The
fuller's earth or equivalent polymerizing catalyst
removes part of the gum and color forming con-
stituents, but leaves intact those unsaturated
compounds which are valuable to gasoline or
other motor fuels for their anti-knock properties.
The fuller's earth removes selectively objection-
able unsaturated compounds and retains simul-
taneously in the fuel valuable unsaturated com-
pounds. Certain of these valuable unsaturates
would, of course, eventually form gum deposits,
but they are prevented from so doing by the addi-
tion to the motor fuel of one or a combination of
the herein described inhibiting agents.

The inhibiting agent may be added prior to
treatment with the polymerizing catalyst, but it
is preferably added afterward. It will also be 40
understood that the polymerizing catalyst (such
as fuller's earth) may be dispensed with, but it is
preferably used to give a better product. In any
case, the inhibiting agent should be used only in
an amount sufficient to substantially inhibit gum 45
formation. These amounts will vary in accord-
ance with the nature of the cracked gasoline or
distillate used, but the amount should not exceed
a fraction of one per cent, in general not more
than 0.3%, and preferably about .06%. In other 50
words, a small proportion of inhibitor should be
used in accordance with the desired needs.

What I claim is:

1. A cracked gasoline normally tending to form
gummy substances upon storage and containing a 55

- polyhydroxyphenanthrene compound in sufficient quantity to retard gum formation.
2. A cracked gasoline normally tending to form gummy substances upon storage and containing a dihydroxyphenanthrene compound in sufficient quantity to retard gum formation.

3. A cracked gasoline normally tending to form gummy substances upon storage and containing dihydroxyphenanthrene in sufficient quantity to retard gum formation.

GEORGE W. AYERS, JR.
